UNITED STATES PATENT OFFICE.

FRED G. DIETERICH, OF WASHINGTON, DISTRICT OF COLUMBIA, ASSIGNOR
TO JOHN U. O'MEARA, OF SAME PLACE.

DESIGN FOR A FRONT FOR VENDING-MACHINES.

SPECIFICATION forming part of Design No. 20,251, dated November 4, 1890.

Application filed October 8, 1890. Serial No. 367,452. Term of patent 7 years.

To all whom it may concern:

Be it known that I, FRED G. DIETERICH, a citizen of the United States, residing at Washington, in the District of Columbia, have invented and produced a new and original Design for a Front for Vending-Machines; and I do declare the following to be a full, clear, and exact description of the same, reference being had to the accompanying drawings, forming a part thereof, in which—

Figure 1 is a front view of my improved design, and Fig. 2 is a central vertical section thereof.

The leading feature of my design consists of a representation of a rectangular-shaped frame, the upper portion a of which has a panel-like portion a' , above which is arranged a row of dentals a'' , above which a laterally-enlarged beaded portion a^3 is shown, on which is mounted an ornamental cap-plate a^4 . Be-

low the panel-like portion an inwardly-bowed shape a^5 is presented, below which shows a trough-like portion a^6 , the whole being mounted on an ornamental base a^7 .

I do not desire to confine myself to the exact ornamentations shown, as these may be varied.

The general outline of my design—*i. e.*, the edges, top, and bottom—has the appearance somewhat of a French clock-front. 30

What I claim is—

The design substantially as herein shown and described.

In testimony whereof I affix my signature in the presence of two witnesses.

FRED G. DIETERICH.
